UNITED STATES PATENT OFFICE.

ARCHIBALD ALLAN, OF NORTH SHIELDS, AND HENRY WILLIAM CLOTHIER, OF WALLSEND-ON-TYNE, ENGLAND, ASSIGNEES TO A. REYROLLE & COMPANY LIMITED, OF HEBBURN-ON-TYNE, ENGLAND, A COMPANY OF GREAT BRITAIN.

OPERATING GEAR OF ELECTRIC SWITCHES.

Application filed January 21, 1926, Serial No. 82,880, and in Great Britain March 20, 1925.

This invention relates to the operating gear of electric switches and has particular reference to operating gear for the main switch or switches of switchgear in which the main switch is removable from the rest of the gear. As an example to which the present invention is particularly applicable may be mentioned oil-break switchgear in which the main oil-break switch with its tank can be removed entirely from the rest of the gear and if desired replaced by another similar oil switch and tank.

According to this invention the plunger rod or like member of the main switch is operatively connected with a rotatable spindle upon which a pinion is mounted. Co-operating with this pinion is a second pinion mounted on a spindle carried in bearings in a fixed frame, such bearings being capable of adjustment to secure proper engagement between the two pinions.

Conveniently the spindle carrying the second pinion is mounted eccentrically in a bearing or housing which is rotatable in the fixed frame. Rotation of this spindle to move the plunger rod and open or close the switch is brought about by a handle or any suitable gear and preferably the connection between this gear and the spindle is through a flexible coupling or universal joint.

This flexible coupling is particularly advantageous when the invention is applied to the operating gear of two-phase or multi-phase switchgear, as it allows for any slight want of alignment between the spindles of the separate phase main switches.

In one construction of gear according to this invention as applied to metal-clad oil-break switchgear in which the main oil-break switch and its tank can be removed in a vertical direction from the rest of the gear, the upper end of the plunger rod of the main switch passes through the top plate or cover of the tank into a tubular extension thereof where it is operatively connected to a spindle mounted in bearings on the extension and furnished with a pinion outside the tubular extension. In the normal operative position of the main switch and its tank this pinion is immediately below a second pinion mounted on a spindle carried in adjustable bearings in part of the fixed portion of the gear. The bearings are eccentrically mounted in discs forming part of a housing

which can be rotated in the frame and thus accurate engagement can be produced between the two pinions. The operative connection between the plunger rod and the spindle mounted in the tubular extension may be by means of a rack and pinion inside the extension.

It will be appreciated that when it is desired to remove the main switch and its tank, this can be done simply by lowering them without any interference with the mechanism of the operating gear, the pinion which is mounted on the tubular extension of the tank simply being withdrawn from its engagement with the other pinion.

If desired mechanism may be provided for ensuring that when the main switch is replaced its pinion and the operating pinion with which it engages shall be in the proper relative positions so that, for instance, the switch itself shall be open and the operating gear in the corresponding position.

In a three-phase switch gear of this description similar operating gear is provided for all three main switches and the connection between the adjustable spindle of the centre-phase main switch and the similar spindle on each side of it is through a flexible coupling or universal joint, thus avoiding the necessity for having the three spindles in exact axial alignment.

In the accompanying drawings,

Figure 1 is a sectional elevation of a portion of one construction of electric switchgear according to this invention.

Figure 2 is a sectional elevation taken at right angles to Figure 1, the left-hand portion being partly in section on the line 2—2 of that figure and the remainder partly in section on the line 2'.

Figure 3 is a side elevation of a detail of Figure 2.

All the figures are merely diagrammatic details of construction and parts not essential to the understanding of the present invention being omitted.

The figures illustrate by way of example part of a three-phase oil-immersed switchgear having a main oil-break switch A for each phase contained in a tank B which, with the switch can, when desired, be removed from the rest of the gear by lowering it by means of the gear C and ropes and pulleys C¹ C².

The upper end of the plunger rod D of the switch is attached to a tube D¹ open at its top end and sliding within a tube E which may be regarded as a tubular extension of the top plate B¹ of the switch tank B to which it is attached by means of a housing E¹. This tube E is provided with a cap E² and a spring F is contained within the tube D¹ and presses against the inside of 10 the cap, thus tending to force the plunger rod D downwards to open the switch.

One side of the tube D¹ is formed as a toothed rack as at D² and in engagement with the teeth of this rack is a pinion G mounted on a spindle G¹ in bearings H on the housing E¹. This spindle bears another pinion J beneath and engaging with a pinion K, which may be called the driving pinion, on a shaft K¹ eccentrically mounted in discs 15 K² which can be turned in their housings K³ to secure proper meshing engagement between the teeth of the pinions J and K. The housings K³ are on the walls of a chamber L between two oil-filled chambers into which 20 pass the upper ends of the conductors leading to the main switch A. These chambers may contain intermediate connections or switches, but with these the present invention is not concerned.

30 The shaft K¹ of each of the main phase switches is joined to its neighbour through flexible couplings M which may be of any known form, and a similar flexible coupling is used to connect all the shafts K¹ to a main 35 operating shaft N which may be rotated by hand, by motor or by any other suitable means to raise the switch rods D and close the switches.

Thus the shafts K¹ can be adjusted by 40 means of the eccentric mountings K² to ensure the proper engagement of the pinions J and K, and owing to the flexible couplings M, the shafts can all be easily connected to and driven by the main operating shaft N, 45 the flexible couplings allowing for any slight difference in alignment.

When any one of the oil switches A with 50 its tank B and top plate B¹ is lowered, the pinion J leaves the pinion K but returns into operative engagement with it when the switch and its tank are replaced.

In normal operation it is naturally essential that the switch shall be open before it is lowered and as it is being replaced, and any 55 convenient interlocking arrangement may be provided to ensure this.

One simple arrangement is shown merely by way of example in Figures 2 and 3 where the main operating shaft N is shown as provided with a wheel or disc N¹ having a tooth or catch N² engaged, when the switches are closed, by a pivoted detent O. This detent is connected by a rod O¹ to a trip lever O², one arm of which is in close proximity to 60 65 the spindle C³ of the raising and lowering

gear C. The handle C⁴ of this spindle is arranged so that before it can be brought into operative engagement with the spindle it must move the lever O² so as to withdraw the detent O from engagement with the tooth N², thus freeing the operating shaft N which is arranged when released to rotate the pinions K into the position which they occupy when the switches are opened.
